UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC-SWITCH DEVICE.

1,203,358.

Specification of Letters Patent.

Patented Oct. 31, 1916.

Application filed September 25, 1911, Serial No. 651,225. Renewed April 3, 1916. Serial No. 88,724.

To all whom it may concern:

Be it known that I, CHARLES J. KLEIN, a citizen of the United States, residing at Milwaukee, in the county of Milwaukee and State 5 of Wisconsin, have invented new and useful Improvements in Electric-Switch Devices, of which the following is a full, clear, concise, and exact description, reference being had to the accompanying drawing, forming 10 a part of this specification.

My invention relates to electric switch devices.

It has among its objects to provide an improved electric switch device which is 15 adapted to make and break an electric circuit with quick snap action.

A further object of my invention is to provide an improved electric switch device provided with improved means for dividing 20 up the spark at the contacts when the circuit is interrupted.

Other objects and advantages of my improved construction will hereinafter appear.

In the accompanying drawings, I have 25 illustrated one form which my invention may assume in practice. My invention is not however limited to this specific form, chosen for purposes of illustration, but may assume other forms.

30 In these drawings:—Figure 1 shows a side elevation of the switch in open circuit position. Fig. 2 shows a similar view of the same in closed circuit position. Fig. 3 shows a side elevation of the same in closed circuit 35 position looking in an opposite direction from Fig. 2. Fig. 4 shows a sectional view of the mechanism on line 4—4 of Fig. 3. Fig. 5 shows a sectional view of one of the operating members on line 5—5 of Fig. 3. 40 Fig. 6 shows a perspective view of one of the movable contact members.

In the construction shown in these drawings, I have for purposes of illustration shown a flush switch mechanism of the type 45 described in my copending application Serial No. 623,904, filed April 28, 1911. As illustrated and described in this application this mechanism includes a pair of spring 50 pressed cam members 1 and 2 which are pivoted on suitable shafts or spindles 3, mounted on an insulating base 4 and are arranged to reciprocate on these shafts with the push buttons 5 and 6 when the latter are operated. The cam members 1 and 2 55 are provided with oppositely inclined ac-

tive surfaces as described in that application and are arranged to oscillate about the spindles 3 upon sleeves 7 under the action of spiral springs 8 when either of the push buttons 5 and 6 is actuated. In a preferred 60 form the push buttons 5 and 6 are arranged to reciprocate through suitable openings in a frame 9 mounted upon the insulating base 4 and extending over the switch mechanism. In order that one of the push buttons may be raised as the other is depressed a pivoted strip 10 is provided arranged to rock about a central pin 11 carried on the insulating base 4. The ends of this strip 10 are slotted 65 as at 12 to pass around the shafts 3 as shown 70 in Fig. 5. In a preferred form suitable nuts 13 are carried upon the ends of the inner sleeves 7 which serve to position the cam members upon these sleeves and also act as bearing surfaces for the slotted ends 75 of the rocking member 10, when the buttons are depressed. In this construction however instead of providing a single movable contact member arranged to reciprocate upon spindles carried upon the base 80 when actuated by the cam members, a plurality of oppositely moving oscillating movable contact members are provided. Suitable means are provided upon these oscillating contact members so that they may engage 85 the active surfaces of the cams 1 and 2 and thus be actuated to move in opposite directions to make or break the circuit.

In a preferred form the oscillating contact members 14 and 15 are pivoted upon a 90 common pivot pin 16 carried upon a suitable support 17 depending from the top of the frame 9. As illustrated in Fig. 6 these contact members are preferably substantially rectangular in cross section and are 95 formed of a suitable insulating material. If desired they may be made of such a shape that a portion of the same may engage the active surfaces of the actuating cams. In a preferred form each of these contact members is however, provided with a plurality of studs or projections 18 upon one of the flat sides of the same, adjacent the perforation through which the pivot pin extends and at points substantially equidistant from the same. Suitable bearing surfaces adapted to engage the active surfaces of the cams are provided upon the movable contact members. In a preferred 100 form I use suitable steel balls 19 as these 105 110

bearing surfaces and set these balls within suitable chambers in the ends of the studs 18. If desired however, other forms of bearing surfaces may be used to accomplish the same results. Each of the contact members 14 and 15 is preferably provided with a plurality of contact surfaces 20 and 21, one of which is considerably larger than the other and both of which are substantially 5 arc shaped as shown in Fig. 6. In a preferred form the two contact surfaces are provided by the use of a single stamped contact plate which is formed in the shape shown in Fig. 6 so that the two contact surfaces of the same lie in substantially parallel planes on opposite sides of the contact member and the connecting neck of these two contact surfaces is seated in a suitable slot 22 in the edge of the movable contact member. In a preferred form the conducting plate forming the contact members 20 and 21 is attached to the body of the movable contact member by means of a suitable pin or screw 23 and the ends of the contact surfaces are slightly out-turned or sprung so that the extremities of the same are slightly spaced apart from the insulating block to give a greater resiliency to the contacts. If desired the ends of the contact plates may 25 be rounded or inturned as at 24.

When the parts are assembled as shown in Figs. 1 and 3 inclusive, the movable contact members are pivoted on opposite sides of the support 17 so that the smaller contact surfaces 21 face each other, while the larger contact surfaces 20 on the opposite sides of the same are on the outer surfaces of the movable contact members. Thus it is seen that when the cam members 1 and 2 are 30 actuated to oscillate these contact members, the two contact surfaces 21 move over each other with a wiping action. The contact surfaces 20—20 are arranged to make contact with stationary contacts 25 and 26 35 which are located on opposite sides of the contact members 14 and 15 and are provided with inturned parallel contact surfaces, so that the contact obtained is a wiping contact tending to reduce the spark and to keep 40 the contacts clean. The stationary contacts 25 and 26, are in a preferred form made as extensions on suitable terminal strips 27 and 28, which are mounted on opposite sides of the insulating base 4 and are provided at 45 their upper ends with binding screws 29 and 30, to which the line conductor may be attached. The contact surfaces 21 are arranged to move over each other with a wiping contact in substantially the same manner as the outer contacts 20 move over the 50 surfaces of the contacts 25 and 26. Thus it is seen that the circuit may be considered to extend from the line through the binding screw 29, the stationary contact 25, one of 55 the contact surfaces 20, its connected inner

contact 21, the adjacent inner contact surface 21, the connected outer contact surface 20, the stationary contact 26 and the binding screw 30 to the line. When the switch is actuated by the reciprocation of the push button, this circuit is broken substantially simultaneously, at a plurality of points, the circuit being broken at the contacts 25 and 26 and at the contact surfaces 21 at the same time so that the series circuit is divided in such a manner as to divide up the arc. Due to the provision of the resilient contacts having out-turned edges, the wiping action of the contacts and division of the arc by breaking the circuit at a plurality of points, the arc at any of the contacts is reduced to such a degree that no injury results to any of the contacts. With the parts in the position shown in Fig. 1 the operation of this form of switch is as follows: When the left hand push button 5 is depressed, the cam member 1 is lowered, rocking the rocking member 10 about its pivot 11, to force up the cam member 2. When the bearing surface 19 of the contact member 14 passes over the crest of the cam member 1, the movable contact member 14 moves upward about its pivot with a quick snap action to the position shown in Fig. 2, wherein the end of the outer contact plate 20 engages the terminal 25 and the bearing surface of the contact member rests at the bottom of the slope of the cam member 1. Since the movable contact member 15 is similarly pivoted but oppositely impelled, this movable contact member moves in the opposite direction, when its bearing surface has passed over the cresting of the cam 2 and its contact plate 20 engages the opposite terminal 26. As these contact members 14 and 15 oscillate in opposite directions about the pivot 16, their inner contact plates 21 engage with a wiping action substantially simultaneously with the engagement of their outer contact surfaces 20 with the terminals 25 and 26. Conversely when the circuit is broken by the depression of the button 6, each of the contact members moves in the opposite direction and the circuit is broken substantially simultaneously at the terminals 25 and 26 and between the contact surfaces 21. Thus it is seen that the circuit is made and broken at a plurality of points, substantially simultaneously so that the arc generated upon a rupture of the circuit is divided up between these several points, in such a manner as to cut it down beyond any dangerous degree.

What I claim as new and desire to secure by Letters Patent is as follows:—

1. In a finger operated electric switch, in combination, two co-axially pivoted relatively movable members, co-operating contacts actuated thereby, and means for substantially simultaneously imparting snap

movements to both of said members to move their contacts into and out of engagement.

2. In an electric switch, in combination, stationary contacts, two relatively movable contact members movable substantially simultaneously into and out of engagement with one another and said stationary contacts, and means for imparting snap movements to said contact members substantially 10 simultaneously.

3. In an electric switch, in combination, two contact actuating members oscillating in different parallel planes, and means associated therewith to simultaneously oscillate 15 said members with a snap action in opposite directions for making and breaking an electric circuit.

4. In an electric switch, in combination, stationary contacts, two oscillating contacts, 20 and means for oscillating said latter contacts in opposite directions to substantially simultaneously engage and disengage one another and said stationary contacts.

5. In a flush switch, in combination, two oscillating members having superposed portions and contacts on said portions, and means provided with oppositely reciprocating push buttons for substantially simultaneously imparting snap movements to said 30 oscillating members in opposite directions for establishing and interrupting electrical connection between said contacts.

6. In a flush switch, in combination, two push button operated devices arranged in a 35 parallel relation and interlocked to move simultaneously in opposite directions, two superposed oscillating members arranged between said devices and operative connections between said oscillating members and 40 said devices for substantially simultaneously oscillating said members in opposite directions upon operation of said devices, and contacts actuated by said oscillating members.

45 7. In a flush switch, in combination, two parallel reciprocating members each provided with a push button, an interlock between said members insuring movement thereof simultaneously in opposite directions, two concentrically pivoted oscillating members arranged between said reciprocating members, and means operatively connecting said oscillating members to said reciprocating members to cause the former to be 50 oscillated simultaneously in opposite directions upon reciprocation of said latter members.

8. In a flush switch, in combination, two parallel reciprocating members each provided with a push button, an interlock be- 60

tween said members insuring movement thereof simultaneously in opposite directions, two oscillating members arranged between said reciprocating members, and means operatively connecting said oscillating members to said reciprocating members to cause the former to be oscillated simultaneously in opposite directions upon reciprocation of said latter members, said means including a convex cam and a concave 65 cam on each of said reciprocating members engaging bearing surfaces on opposite sides of the center of one of said oscillating members.

9. In an electric switch, in combination, 70 an oscillating contact actuating member provided on opposite sides of its pivot with bearing surfaces, and a reciprocating member having pivoted thereon two cams one concave and the other convex, and a spring 80 pressing said cams against said bearing surfaces of said oscillating member.

10. In combination, an insulating base, a frame mounted thereon, a plurality of standards mounted on said base, a plurality 85 of push buttons arranged to reciprocate through said frame and upon the ends of said standards, a plurality of spring-pressed pivoted cam members arranged to reciprocate with said push buttons and oscillate 90 about their pivots and a plurality of oppositely movable oscillating contact members pivoted to a depending portion of said frame between said cam members, said movable contact members having a portion of the 95 same extending into the path of said cam members.

11. In an electric switch, in combination, two relatively movable members having co-operating contacts on adjacent sides thereof 100 and extensions of said contacts on the outside thereof, and stationary contacts to be engaged by said extensions.

12. In an electric switch, in combination, two relatively movable members having co-operating contacts on adjacent sides thereof and extensions of said contacts on the outside thereof, and stationary contacts to be engaged by said extensions, said members being movable simultaneously to actuate 110 said first mentioned contacts to simultaneously engage and disengage one another and also said stationary contacts.

In witness whereof, I have hereunto subscribed my name in the presence of two witnesses.

CHARLES J. KLEIN.
